(57) **CLAIM**

The ornamental design for a device for surgical gas transmission as shown and described.

DESCRIPTION

FIG. 1 is a right front perspective view of a device for surgical gas transmission showing my new design.

FIG. 2 is a right side view thereof.

FIG. 3 is a left side view thereof.

FIG. 4 is a front view thereof.

FIG. 5 is a back view thereof.

FIG. 6 is a top view thereof; and,

FIG. 7 is a bottom view thereof.

The dash-dash lines shown in the figures depict portions of the device for surgical gas transmission that form no part of the claimed design.

The separations depicted by the dot-dash break lines in the figures indicate an indeterminate length. Any portion of the article between the break lines forms no part of the claimed design.
